UNITED STATES PATENT OFFICE.

ALBERT SHEPARD TITCOMB, OF PROVIDENCE, RHODE ISLAND.

POWER BOAT.

Application filed April 23, 1926. Serial No. 104,091.

This invention relates to an improved construction of power boat; and has for its object to provide such a boat which will offer the minimum resistance to being propelled rapidly through or on the surface of the water.

A further object of this invention is the provision of fins or blades disposed edge-ways along the opposite edges of the bottom 10 of the boat extending from the stern forward to restrict the lateral flow of the surface water and trap the air beneath the bottom to assist in lifting the boat to plane upon the surface.

15 A still further object of the invention is to set these blades or fins on an outwardly inclined angle to enlarge or increase the planing surface or area to further assist in lifting and supporting the boat to plane 20 while speeding.

My invention further consists in extending the bottom surface of the boat rearwardly beyond the stern transom to again increase the planing area and also to prevent 25 back draft or suction of the water permitting the boat to leave the water smoothly while speeding.

A still further object of the invention is to provide a standardized type of hull that 30 may be built at the minimum expense and in unit form, the same being preferably constructed of corrosion resisting sheet metal. The upper edges of the side walls of the hull being preferably flanged to stiffen the same 35 and provide a chafing strip therefor and also to provide a suitable surface on which the superstructure, of any desired design, may be supported and to which it may be readily attached, preferably by an electro welding process.

With these and other objects in view, the invention consists of certain novel features of construction, as will be more fully described, and particularly pointed out in the 45 appended claims.

In the accompanying drawings:

Figure 1 is a perspective view showing the body portion of my improved motor boat hull with one design of superstructure 50 mounted thereon.

Figure 2 is a side elevation of the construction shown in Figure 1.

Figure 3 is a central sectional elevation of the same.

55 Figure 4 is a longitudinal section of the

hull portion and one form of superstructure shown in dotted lines.

Figure 5 is a plan view of the bottom of the boat showing the broad planing surface with its central concaved portion at the after 60 portion formed to receive the driving propeller also showing the flaring fins or blades bending inward to vertical position at the bow.

Figure 6 is a stern view of the hull portion.

Figure 7 is a bow view of the hull portion.

Figure 8 is a section on line 8—8 of Figure 4.

Figure 9 is a section on line 9—9 of Figure 4.

Figure 10 is a section on line 10—10 of Figure 4.

Figure 11 shows the bottom plates as secured to the side walls by electro welding 75 an angle iron along the meeting edges thereof.

Figure 12 shows the outer edge of the bottom portion as turned downwardly to support and stiffen the lower flanged edge 80 of the side walls to form the fin or blade and to be supported by this angle iron at the inner meeting joints.

It is found in the practical construction and operation of motor boats particularly 85 those designed to be driven at a high or moderately high rate of speed, of advantage to so construct the hull that it will offer the least resistance to the water through which or over which it is forced and to so form 90 the bottom portion that as the speed increases the hull will lift to ride over or along the surface of the water instead of through it; and to accomplish this in a simple and effective way, I have provided a boat which 95 is substantially the same width throughout its length offering a broad planing surface on which the boat is supported while planing, and also, it is found of advantage to provide relatively deep fins or blades on the side edges of the boat to confine the water and air under the boat, and prevent 100 it from spreading out or escaping laterally under pressure of the weight of the boat 105 to assist in lifting the boat to ride on the surface of the water; and the following is a detailed description of the present embodiment.

ment of my invention and showing one construction of motor boat by which these advantageous results may be accomplished:—

With reference to the drawings, 10 designates the body or hull of my improved boat, the same being preferably constructed of corrosion resisting sheet metal, and the edges of its metal plates connected together by an electrowelding process. This boat is 10 preferably so shaped that the bow 11 is substantially of the same width as the stern 12 thus forming side walls 13 substantially parallel with each other. The bottom 14 is 15 preferably formed flat and its surface at the stern thus provides a broad surface 15 for supporting the boat on the surface of the water and this surface extends from the stern forward substantially to the point 16 where it is inclined slightly upward to a point 17 20 from which latter point it is turned more sharply upward to form the bow 18 of this hull or body portion. The middle portion of this broad bearing surface of the stern is preferably grooved as at 19 to permit a free 25 flow of water to the propeller wheel 20 which is mounted on the end of the driving shaft 21.

In order to cause the boat to leave the water smoothly and without back draft or 30 suction, I preferably set the stern transom 22 inwardly from the stern edge 23 of the bottom plates. The after ends of the side wall plates 13 also extend beyond the stern transom to further assist in preventing the 35 water under side pressure from too readily entering the air space or pocket formed at the stern by the rapidly speeding boat.

In order to trap the air entering beneath the boat and to also prevent the free lateral 40 movement or spreading of the supporting film of water beneath the boat, I have provided a longitudinally extending fin or blade 25 set edgeways to extend from the stern forwardly a substantial distance along 45 the length of the boat 16 which is normal, and in order to provide a broader bearing and greater planing surface or area for supporting the boat while speeding, I 50 preferably turn the bottom edges of these fins or blades slightly outwardly or so arrange them that their inner faces are set on an incline or at an obtuse angle to the plane of the bottom surface of the boat, which arrangement when extending beyond the sides 55 of the boat may serve to increase the supporting and planing surface of the boat and also serve to reduce the frictional resistance of the water against the sides thereof by minimizing the lateral pressure of the water 60 against these sides.

In order to reduce the resistance of these fins in entering the water as the boat is traveling, I form their forward end portions substantially vertical as at 26, see Figures 65 5 and 8, back for a short distance from the

bow where their lower edges begin to bend or flare outwardly as at 27, to meet the inclined portions. In other words, the forward upwardly projecting portions of these fins or blades are set vertically and the horizontally-disposed portions of the blades are set on an outward incline. 70

The meeting edges of the bottom plates 15 and the side wall plates of the hull are preferably electrowelded together; also in some 75 instances, the side plate 13 may extend down below the bottom as shown in Figure 11, to form the fin 25, while in other instances, if desired, the bottom plate 15 may also be turned down as at 29 in Figure 12, to reinforce this fin 25. 80

In some instances in constructing the metal hull, I turn the upper edges of the side walls outwardly as at 30 to stiffen the sides of the boat, provide a convenient protecting chafing strip therefore, and also provide a suitable edge surface for supporting the desired design of superstructure, and to which edge this superstructure may be fastened, preferably by an electrowelding process. 85

My improved construction of the sheet metal hull portion of the boat is so formed that it may be built very rapidly and at the minimum expense, the joints may be 90 homogeneously connected together by an electrowelding process thus providing a boat to all intents and purposes of one homogeneous piece easy to manufacture of standardized design for quantity production. 95

I have shown and described the planing fins as extending downwardly and outwardly beyond the side walls of the hull of the boat but I desire it to be understood that I do not limit myself to this exact arrangement of these fins as their position relative to the side walls of the hull may be varied somewhat without departing from the spirit and scope of my invention. 105

In some instances it is found of advantage to form the bottom of the boat of a continuous metal plate extending from bow to stern; also to in some instances form the fin or rib integral with this bottom plate, one arrangement of which is herein illustrated 110 at 24 in Figure 12.

The foregoing description is directed solely towards the construction illustrated, but I desire it to be understood that I reserve the privilege of resorting to all the mechanical changes to which the device is susceptible, the invention being defined and limited only by the terms of the appended claims. 120

I claim:

1. A motor boat having a hull of the hydroplane type formed with substantially parallel sides and a bottom surface substantially flat from the stern forward for a substantial portion of the length of the hull, and a longitudinally-disposed fin or blade set 125

- edgewise along either edge of the hull, the forward portion of the fins each being set substantially vertical with its lower edge gradually bending outwardly as it extends 5 rearwardly to meet said inclined disposed portion of the fin.
2. A motor boat having a hull with substantially parallel sides and a broad flat planing bottom surface at the after portion 10 of the hull, said surface being grooved for a short distance from the stern forward, and a fin or blade of substantial depth extending from the stern along the opposite bottom edges of the hull.
- 15 3. A motor boat having a hull with substantially parallel side walls, a stern transom and a broad flat planing bottom surface extending rearwardly beyond said transom, and fins or blades of substantial depth extending 20 from the stern along the opposite edges of the bottom of the hull, said fins or blades being set at an obtuse angle to the flat bottom surface of the boat to further extend its planing, the lower edge of each fin bending 25 inwardly to substantially vertical position at the forward end thereof.
4. A motor boat hull unit formed of sheet metal and having side walls set substantially parallel throughout their length and connected by a broad flat bottom portion, the 30 forward portion of the bottom being turned up slightly towards the bow, said side walls being relatively narrow extending but a short distance above the normal load water line when the boat is at rest and having 35 flanged edge portions on which any desired design of superstructure may be supported and fastened.
5. A motor boat hull unit formed of sheet 40 metal with a broad flat planing bottom surface extending forward from the stern, turning gradually upward toward the bow of the boat, the hull having substantially parallel relatively narrow side walls extending but a 45 short distance above the normal load water line when the boat is at rest, the upper edge
- of these sides being turned outwardly to provide a stiffening flange, and a support to which different designs of superstructures may be supported and fastened. 50
6. A motor boat hull unit formed of sheet metal and having side walls set substantially parallel throughout their length and connected by a broad flat bottom portion, the forward portion of the bottom being turned 55 up slightly towards the bow said side walls being relatively narrow extending but a short distance above the normal load water line when the boat is at rest and having flanged edge portions on which any desired 60 design of superstructure may be supported and fastened, and a longitudinally-disposed fin or blade of substantial depth set edgewise along the opposite edges of the boat.
7. A motor boat hull formed of sheet material having a bottom portion with side walls supported thereon and extending the 65 length of the hull, said walls being relatively narrow extending but a short distance above the load water line, the upper portion of 70 said walls being shaped to receive and support different desired designs of superstructures and to present a surface to which these superstructures may be secured.
8. A motor boat having a hull with substantially parallel sides, a broad substantially flat planing bottom plate at the after portion of the boat and guide fins along the 75 opposite side edges of the boat formed integral with said bottom plate.
9. A motor boat having a hull with substantially parallel sides, the bottom of the boat being formed of a single continuous metal plate extending from bow to stern and having a broad after bearing portion with the forward portion curved upwardly, and a fin or rib formed integral with this bottom plate and extending forwardly from the stern along either edge of the boat. 80

In testimony whereof I affix my signature.

ALBERT SHEPARD TITCOMB.
